UNITED STATES PATENT OFFICE.

FRANK. L. MCQUISTON, OF GREENCASTLE, IOWA.

CAR-COUPING.

SPECIFICATION forming part of Letters Patent No. 293,053, dated February 5, 1884.

Application filed May 4, 1883. (No model.)

To all whom it may concern:

Be it known that I, FRANK. L. MCQUISTON, of Greencastle, in the county of Jasper and State of Iowa, have invented a new and useful Improvement in Car-Couplings, of which the following is a full, clear, and exact description.

Reference is to be had to the accompanying drawings, forming a part of this specification, in which similar letters of reference indicate corresponding parts in all the figures.

Figure 1 is a plan view of my improvement. Fig. 2 is a front elevation of the same. Fig. 3 is a side elevation of the same, partly in section through the line *x x x*, Fig. 1. Fig. 4 is a side elevation of a twisted link.

The object of this invention is to facilitate the operation of coupling and uncoupling cars and promote security in such operation.

The invention consists in a car-coupling constructed with a draw-head having attached to it a cross-bar provided with bearings, in which slides a rod provided with stop-pins and a spring, and carrying a coupling-pin bent to pass horizontally through the draw-head, and a link-raising elbow, as will be hereinafter fully described.

A represents the draw-head, which is secured in the ordinary manner to bars B, attached to the frame C of the car. The draw-head A is made like the draw-head of an ordinary car-coupling, except that the opening for the link is so made as to receive a link standing in a vertical plane, or edgewise, instead of lying horizontally, and also has a recess in its lower side.

To the lower side of the draw-head A, at a little distance from its forward end, is secured a cross-bar, D, to the forward side of which are attached arms or bearings E, to receive the rod F, that carries the coupling-pin G. The coupling-pin G is bent at right angles, and passes horizontally through the draw-head A and through the coupling-link H, placed within the said draw-head.

Upon the shank of the coupling-pin G is formed a sleeve to fit upon the rod F, and which has a short slot formed in it to receive the pin or screw I, to cause the said rod to carry the said coupling-pin G with it in its longitudinal movement, while allowing the said rod to have a partial revolution within the said sleeve. The longitudinal movement of the

rod F in one direction is limited by the shank of the pin G striking against the side of the draw-head A, and in the other direction by 55 the sleeve of the pin G, or by a stop-pin, J, attached to the said rod, and which strikes against one of the bearings E, the said stop being arranged in such a position as to stop the movement of the said rod F before the 60 coupling-pin G has been fully withdrawn from the hole in the draw-head A. The rod F is held forward, holding the pin G in a coupled position, by a spiral spring, K, placed upon the said rod F, with one end resting against 65 the bearing E, and its other end resting against a pin, L, or other stop, attached to the said rod F.

To the rod F is attached an elbow, M, in such a position as to be directly below the 70 recess in the lower side of the draw-head A, so that by slightly turning the said rod F the projecting end of the link H can be raised and lowered to guide it into the draw-head A of an advancing car by a person at the side 75 of a car. When the coupling-pin G has been drawn back to uncouple the cars, by slightly turning the rod F, the elbow M will be brought into position to rest against the side of the draw-head A and lock the said coupling-pin 80 G in an uncoupled position.

The cars are coupled by turning the rod F to withdraw the elbow M from the side of the draw-head A and allow the coupling-pin G to be forced through the said draw-head and 85 the coupling-link H by the action of the spring K.

The rod F is provided with handles N, for convenience in turning it to couple and uncouple the cars.

A car provided with my improved coupling can be coupled with a car having an ordinary coupling by using a link made with a half-twist, as shown in Fig. 4.

Having thus fully described my invention, I claim as new and desire to secure by Letters Patent—

1. A car-coupling constructed substantially as herein shown and described, and consisting of the draw-head A, the cross-bar D, having bearings E, the rod F, having stop-pins I J L, the spring K, the elbow M, and the bent coupling-pin G, as set forth.
2. In a car-coupling, the combination, with

the draw-head A, of the sliding rod F, having stop-pins I J L, the spring K, the elbow M, and the bent coupling-pin G, substantially as herein shown and described, whereby the cars 5 can be coupled by operating the said rod, as set forth.

3. In a car-coupling, the combination, with the draw-head A, having a recess in its lower side, and the sliding rod F, carrying the bent 10 coupling-pin G, of the elbow M, substantially as herein shown and described, whereby the

link can be guided into the draw-head of an adjacent car, as set forth.

4. In a car-coupling, the combination, with the slide-rod F, having pin I, and the coupling-pin G, having slotted sleeve, of the link-lifter M, whereby the link may be lifted without moving the pin, as described. 15
